COMBINATION BRUSH, HOLDER, AND COSMETIC CONTAINER

Joseph L. La Mura, Livingston, N. J., assignor to Joanell Company, Livingston, N. J., a partnership composed of Anthony La Mura and Joseph L. La Mura

Application November 1, 1949, Serial No. 5,818

Term of patent 7 years

(Cl. D9—2)

To all whom it may concern:

Be it known that I, Joseph L. La Mura, a citizen of the United States of America and a resident of Livingston, in the county of Essex and State of New Jersey, have invented a new, original, and ornamental Design for a Combination Brush, Holder, and Cosmetic Container, of which the following is a specification, reference being had to the accompanying drawing, forming a part thereof.

Fig. 1 is a side elevational view of a combination brush, holder, and cosmetic container, showing my new design with the parts in closed position;

Fig. 2 is a view of Fig. 1 turned 90°;

Fig. 3 is a view of Fig. 1 turned 180°;

Fig. 4 is a side elevational view thereof with the container part in open position;

Fig. 5 is an exploded view thereof;

Fig. 6 is a cross-sectional view thereof taken on line 6—6 in Fig. 1;

Fig. 7 is an end view thereof looking toward the container end in the direction of arrows 7—7 in Fig. 1;

Fig. 8 is an end view thereof looking in the direction of arrows 8—8 in Fig. 3; and

Fig. 9 is a side elevational view of the brush part of Fig. 5 turned 90°.

I claim:

The ornamental design for a combination brush, holder, and cosmetic container, as shown and described.

JOSEPH L. LA MURA.
